[57] CLAIM

The ornamental design for a combined fluorescent light and radio, as shown and described.

DESCRIPTION

FIG. 1 is an underneath plan view of a combined fluorescent light and radio showing my new design;

FIG. 2 is a left side elevational view thereof;

FIG. 3 is a front elevational view thereof;

FIG. 4 is a top plan view thereof;

FIG. 5 is a right side elevational view thereof;

FIG. 6 is a rear elevational view thereof;

FIG. 7 is a left side elevational view showing fluorescent light raised;

FIG. 8 is a front elevational view showing fluorescent light raised;

FIG. 9 is a right side elevational view showing fluorescent light raised;

FIG. 10 is a rear elevational view showing fluorescent light raised;

FIG. 11 is a front elevational view showing fluorescent light pivoted;

FIG. 12 is a front elevational view showing fluorescent light raised and pivoted;

FIG. 13 is a right side elevational view showing fluorescent light raised and pivoted;

FIG. 14 is a front elevational view showing fluorescent light in an alternative position, raised and pivoted;

FIG. 15 is a front elevational view showing fluorescent light in a further alternative position, raised and pivoted;

FIG. 16 is a right side elevational view showing fluorescent light raised and turned;

FIG. 17 is a sectional view on left side; and,

FIG. 18 is a sectional view on front elevational view.
